(57) **CLAIM**

We claim the ornamental design for the oral and topical syringe, as shown and described.

DESCRIPTION

FIGS. 1-7 illustrate an oral and topical syringe, showing our new design;

FIG. 1 is a top isometric view of an oral and topical syringe;

FIG. 2 is bottom isometric view thereof;

FIG. 3 is a left side view thereof, the right side view being a mirror image;

FIG. 4 is a front view thereof, the rear view being a mirror image;

FIG. 5 is a top view thereof;

FIG. 6 is a bottom view thereof;

FIG. 7 is a cross-sectional view thereof, taken along a vertical plane;

FIG. 8 is an exploded view thereof;

FIG. 9 is a bottom isometric bottom view thereof in which the plunger is in an extended state;

FIGS. 10-14 illustrate the barrel, with the plunger removed and not shown;

FIG. 10 is a bottom isometric view of the barrel, with the plunger removed and not shown;

FIG. 11 is a bottom view thereof;

FIG. 12 is a top view thereof;

FIG. 13 is a front view thereof, the rear view being a mirror image;

FIG. 14 is a left side view thereof, the right side view being a mirror image;

FIGS. 15-19 illustrate the plunger, removed from the barrel and in which the barrel is not shown;

FIG. 15 is a bottom isometric view of the plunger, removed from the barrel and in which the barrel is not shown;

FIG. 16 is a left side view thereof, the right side view being a mirror image;

FIG. 17 is a front view thereof, the rear view being a mirror image;

FIG. 18 is a top view thereof; and,

FIG. 19 is a bottom view thereof.
